TUBULAR FABRIC.

1,016,527.

Specification of Letters Patent.

Patented Feb. 6, 1912.

Application filed August 1, 1911. Serial No. 641,816.

To all whom it may concern:

Be it known that I, CHARLES S. SMITH, a citizen of the United States, and a resident of Providence, in the county of Providence and State of Rhode Island, have invented certain new and useful Improvements in Tubular Fabrics, of which the following is a specification.

The present invention relates to tubular woven fabric such as that commonly used for insulating electric conductors.

The object of the invention is to provide a tubular woven fabric of such material, and with the strands of such form and in such relationship, that the conduit will meet all underwriters' requirements when employed for containing electric conductors.

Of the accompanying drawings, which illustrate one form in which the present invention may be embodied,—Figure 1 represents a longitudinal elevation, partly in section, on a comparatively large scale, of a piece of tubular woven fabric, the weave being shown loose or open to better illustrate the manner in which the article is made. Fig. 2 represents an elevation of a strand composed of a plurality of strips twisted together. Fig. 3 represents an elevation of a strand consisting of a single strip which is twisted. Fig. 4 represents an elevation of a strip in its incipient stage of being crumpled to form a strand like that shown in Fig. 3. Fig. 5 is a view similar to a portion of Fig. 1 but illustrating the closeness of the weave as actually made.

The same reference characters indicate the same parts wherever they occur.

The tubular fabric, as represented by Fig. 1, is woven, as distinguished from 40 braided; that is to say, it comprises longitudinal strands and helical strands, the strands 10 being comparatively soft and flexible and the strands 11 being comparatively hard and stiff. According to the arrangement shown, 45 the soft strands 10 constitute the warp, and the hard strands 11 constitute the weft or filling. The manner of weaving the strands 10 and 11 forms no part of the present invention, the invention residing wholly in the 50 article illustrated in Fig. 5.

Referring to Fig. 2, the strand 11 shown thereby is composed of a plurality of strips 12 crumpled laterally and twisted together to make the strand circular in cross section 55 and thick and comparatively hard and stiff.

The strips 12 may be made of any suitable sheet material, such as thin paper, and when more than one is used for a strand, they are preferably laid in layers before being crumpled and twisted.

The tubular fabric represented by Fig. 1 comprises two hard-twisted helical weft or filling strands, each of which is made in the manner shown by Fig. 2. The warp strands 10 may be made of cotton or any other suitable material, but, while the strands 11 are thick and comparatively hard and stiff for the purpose of lending firmness, the strands 10 are preferably soft and comparatively flexible for the purpose of facilitating the weaving operation and to secure a close tight weave.

The structure shown, while imparting all the necessary strength against pressure, allows enough longitudinal flexibility to permit the conduit to be led and laid wherever required, because the portions of the relatively soft material of the strands 10 where they cross each other between the strands or coils 11 of harder material, will yield to permit the coils to approach each other along the concave side of the curve in which the conduit is being laid, and to correspondingly open along the convex side of that curve. And this occurs without any such interruption of the close nature of the weave as to ever necessitate an extra wall or covering.

I do not wish to be limited to the number of strands shown, for whereas Fig. 1 illustrates tubular fabric having two weft strands 11, similar fabric might be made by using one or any number of helical weft strands.

The strand 11* represented by Fig. 3 consists of one strip instead of a plurality of twisted strips twisted together. This form of strand, although somewhat different from the form shown by Fig. 2, is nevertheless adapted to be used in the same manner and with the same result. The tubular fabric may be saturated or coated with any suitable compound for rendering it waterproof or noncombustible, or if desired, the compound may be administered to the strands prior to the weaving operation. The fabric may be used for a conduit or covering or for any other purpose. The circular cross section of the weft resulting from the twisting of the thin material imparts sufficient

rigidity to the article to resist distortion due to crushing strain, and further permits such close weaving of the warp and weft that no additional covering is required, the article as described, being capable of being saturated with moisture proof material. It will be readily understood of course, that the weaving operation will draw the strands 10 very much closer around the strands 11 than indicated in Fig. 1 of the drawings, in which figure the weave is represented as comparatively open in order to better illustrate the structure. Fig. 5 illustrates the correct relationship of the strands.

15 The twisting of the thin material of the strands 1^b necessarily renders said strands hard and substantially circular in cross section. When the strands 10 are closely interwoven therewith, the tubular article 20 needs no additional outer wall or shell, because the hardness of the strands 11, and their transverse circular formation, imparts all necessary rigidity to the tube to resist distortion due to the crushing strain. In 25 this respect my improved tubular fabric differs materially from one having flat or nearly flat weft or filling strands, the shape of which is such as to preclude the tube from having much strength unless such 30 strands are made of metal which latter would of course be objectionable if the tube is to be used as a conduit for electric conductors.

By the term hard-twisted, I mean that the 35 thin material which comprises the strands 11 is twisted to a sufficient degree of tightness to make the said strands so hard that they will be quite rigid, and will preserve the form of the strands 10 with no straight 40 portions but having a series of continuous uniform in-and-out curves, the inner curves being equal to the outer curves, whereby the

complete tubular fabric is rendered exceedingly strong and rigid without the employment of any outer shell. The longitudinal 45 strands 10 have equal alternating interior and exterior curves which substantially describe semi-circles and closely fit the exterior of the helical strands 11. And the helical strands are held firmly against lateral movements. Furthermore, the crossing portions of adjacent longitudinal strands are gripped so tightly by the helical strands that a tight structure is formed and one that resists collapsing due to external pressure. 50 At the same time this provides sufficient flexibility for the purpose of conduits for 55 electric conductors.

I claim:

1. A tubular fabric comprising longitudinal strands, and a helical twisted strand substantially circular in cross section closely interwoven with the longitudinal strands, said helical strand being composed of thin paper, the twisting of the thin material rendering it thick and comparatively hard and stiff, and capable of providing the necessary rigidity without an additional outer wall or shell.

2. A tubular fabric adapted for use as a 70 conduit for electric conductors, said fabric comprising longitudinal and helical strands, the latter being of hard-twisted paper, the said longitudinal and helical strands being 75 tightly interwoven whereby a strong tube having a wall of a single thickness is provided.

In testimony whereof I have affixed my signature, in presence of two witnesses.

CHARLES S. SMITH.
